OF TOLEDO, OHIO, A CORPORATION OF OHIO

GLASS ANNEALING LEER

Application filed December 3, 1930. Serial No. 499,698.

The present invention relates broadly to an apparatus for forming and annealing sheet or plate glass, and more particularly to a roller type glass annealing leer.

The leer herein provided is primarily intended to operate in conjunction with a glass rolling apparatus of the intermittent type. In the production of successive sheets of glass by an intermittent rolling operation, it is desirable that the formation of the sheet be performed at a relatively great speed as compared to the speed at which it travels in annealing. This rapid formation of the glass sheet is desirable from both the standpoint of production and quality, while the forward travel of the sheet during annealing is necessarily slow in order to avoid making the annealing apparatus of great length.

According to the present invention, there is provided a leer of this type including two sets of rolls movable alternately into supporting engagement with the sheet and adapted to carry the said sheet successively forwardly and then backwardly at a speed either equal or substantially equal to the speed of sheet formation, the rearward movements of the sheet being relatively less than the forward movements thereof whereby it has a step by step passage through the leer, with the progress of the sheet as a whole being substantially slower than the rate of sheet formation. In other words, the sheet is reciprocated within the leer with the distance it travels rearwardly during each reciprocation being less than the distance it travels forwardly so that there will be a general retarded advance of the sheet through the leer as a whole. The alternate forward and rearward movement of the glass gives the effect of a much longer leer than that actually employed, and as a consequence of which much more efficient annealing is achieved. Also, by maintaining the sheet in constant endwise motion at a speed equal or substantially equal to the rate of formation thereof, the tendency of the sheet to sag between the rolls will be minimized and a more uniform surface obtained.

Other objects and advantages of the invention will become more apparent during the course of the following description when

taken in connection with the accompanying drawings.

In the drawings forming a part of this application and wherein like numerals are employed to designate like parts throughout the same,

Fig. 1 is a vertical longitudinal section through apparatus provided by the present invention, and showing the forward or receiving end portion of the annealing leer,

Fig. 2 is a top plan view thereof,

Fig. 3 is a side elevation of a portion of the leer showing one type of means which may be employed for raising and lowering the sheet supporting rolls,

Fig. 4 is a similar view of an alternative arrangement, and

Fig. 5 is a sectional view taken substantially on line 5—5 of Fig. 2.

Referring to the drawings, 5 designates a receiver or support adapted to receive thereupon from a pot or other suitable receptacle 6 a mass or charge of molten glass 7 to be reduced to sheet form. The molten glass is preferably supplied to the receiver 5 when the same is in a substantially horizontal position as indicated by the broken lines in Fig. 1, after which the pot 6 is removed and the receiver tilted upwardly to cause the molten glass to move downwardly between a pair of forming rolls 8 and 9 which roll the glass to a sheet 10 of substantially predetermined and uniform thickness. The forming rolls are spaced from one another to create a sheet forming pass therebetween and are mounted upon shafts rotatably supported at their opposite ends by members 11 and 12.

As pointed out above, it is desirable that the molten glass be rapidly reduced to sheet form and the forming rolls 8 and 9 are consequently driven at a relatively high peripheral speed during the supplying of the molten glass thereto. One of the forming rolls may be positively driven as by suitable driving means 13, and the other roll driven from the first roll through intermeshing gears 14 mounted upon the roll shafts.

The glass sheet or plate 10 made by the forming rolls is supported upon and guided downwardly as it leaves the forming rolls

by an inclined apron or chute 15 by means of which it is deflected into a substantially horizontal plane. Positioned adjacent the chute 15 and adapted to receive the glass sheet or plate therefrom is a horizontal conveyor or runway section 16 preferably composed of a plurality of horizontally aligned rolls 17 mounted upon shafts which are rotatably supported at their opposite ends in side frames 18 and 19 and being driven in any desired manner such as by keying to the shaft of each roll a sprocket 56 and training about all of the sprockets a driven sprocket chain 20. The rolls 22 are adapted to be driven 15 at all times at a speed substantially equal to the speed of sheet formation.

Arranged at the end of the runway 16 and adapted to receive the sheet therefrom is the annealing leer 21 of the roller type and including a relatively large number of sheet supporting and conveying rolls. These rolls are divided into a plurality of sections disposed end to end throughout substantially the entire length of the leer, two adjacent sections being indicated at A and B. Each section is composed of two sets of rolls 22 and 23, with the rolls of said sets being arranged alternately with respect to one another. The rolls 22 are forwardly driven rolls operating 30 at all times to advance the sheet forwardly through the leer and are driven at the same speed as the runway rolls 17 which is substantially equal to the rate of formation of the sheet. On the other hand, the rolls 23 35 are rearwardly driven rolls operating at all times to move the sheet rearwardly within the leer and may be driven either at a speed equal to the rate of sheet formation or at a relatively slower speed. The sets of 40 rolls 22 and 23 of each roller section are also vertically movable relative to one another to bring them alternately into supporting engagement with the glass sheet so as to successively move the said sheet first forwardly 45 and then rearwardly within the leer. In other words, the sheet is being constantly reciprocated within the leer while, at the same time, advancing forwardly through the leer in a step by step fashion as will be more clearly hereinafter apparent.

The forwardly operating rolls 22 of each roller section A, B etc. are carried by shafts 24 which project through the side walls of the leer and are rotatably supported at their opposite ends by the horizontal supporting members 25 and 26. For the purpose of driving the rolls 22, there is carried by each of the shafts 24 at one side of the leer a sprocket 57 and trained about all of these sprockets is 55 a sprocket chain 27 driven from a motor 28. This motor 28 is provided with a shaft 58 upon which is mounted a sprocket 59. Trained about this sprocket is a sprocket chain 29 also trained about a relatively larger sprocket 60 keyed to a shaft 61 journaled in

bearings carried by the supporting member 25. Also fixed upon shaft 61 is a second sprocket (not shown) about which is trained the lower horizontal flight of sprocket chain 27. The motor 28 can also be utilized to drive the runway rolls 17 and this can be accomplished by passing the sprocket chain 27 about a sprocket 62 carried at the corresponding end of the first adjacent roll 17. Obviously however an independent drive for the rolls 17 may be provided if preferred. In order to maintain the sprocket chains 27 and 29 tight upon raising and lowering of the rolls 22, there are provided the two chain tighteners 63 and 64 respectively. The chain tightener 63 is in the form of a freely rotatable sprocket engaging the upper horizontal flight of chain 27, said sprocket being carried by a bracket 65 secured to the side wall of the annealing leer. Likewise, the tightener 64 75 is in the form of a sprocket engaging the lower inclined run of the chain 29 and being carried by a stationary bracket 66. In Fig. 5, the rolls 22 are shown in their raised or elevated position, and it will be readily apparent that upon lowering of these rolls, the sprockets 63 and 64 will maintain the chains 27 and 29 respectively tight. The rearwardly operating rolls 23 of each roller section A, B etc. are carried upon shafts 31 which also project through the side walls of the leer and are supported at their opposite ends by the horizontal members 32 and 33. The rolls 23 can be driven in the same manner as rolls 22 80 from a motor 34.

The means employed for moving the sets of rolls 22 and 23 of each roller section vertically with respect to one another so as to shift the sheet from one set of rolls to the other is illustrated in Figs. 3 and 4 and may be briefly described as follows:—Secured to and connecting the adjacent ends of the supporting members 25 and 32 at one side of the leer and the adjacent ends of the supporting members 26 and 33 at the opposite 95 side of the leer is a rocker support 37 pivoted intermediate its ends as at 38 to a fixed block 39 and to the adjacent ends of the respective supporting members 25—32 or 26—33 as at 100 40 and 41. The rocker support 37 is formed 105 with a depending portion 42 to the lower end of which is pivoted as at 43 a pitman 44 and, upon reciprocation of this pitman, the support 37 will be rocked about its pivot 38 to alternately raise and lower the sets of rolls 110 22 and 23. Of course, it will be understood that similar operating means is provided at both ends of the supporting members at each 115 side of the leer.

In the event the rearwardly operating rolls 23 were maintained in contact with the sheet the same length of time as the forwardly operating rolls 22 and were also driven at the same peripheral speed, it will be seen that the sheet would be moved rearwardly within the 120 125 130

leer by the rolls 22 the same distance it was moved forwardly by rolls 23, as a result of which there would be no progress of the sheet as a whole forwardly through the leer. According to the present invention, however, and in order to cause the sheet to advance forwardly through the leer in a step by step fashion the rolls 23, acting to move the sheet rearwardly, may be driven at a slightly 10 slower peripheral speed than rolls 22 or may be driven at the same peripheral speed but not maintained in engagement with the sheet for as long a period as the forwardly operating rolls, to the end that the rearward movement of the sheet during each reciprocation 15 will be relatively less than its forward movement and, in this manner, there will be a general retarded advance of the sheet through the leer as a whole. The advancement of the 20 sheet through the leer may also be effected by driving the two sets of rolls 22 and 23 at the same rate of speed and maintaining them in engagement with the sheet the same length of time by providing rolls 22 of a slightly 25 greater diameter than rolls 23.

With the above in mind, the means disclosed in Fig. 3 for reciprocating the pitman 44 to alternately raise and lower the rolls 22 and 23 includes an eccentric 45 to which the 30 pitman is pivoted as at 46. The eccentric 45 carries a gear 47 meshing with a worm 48 on drive shaft 49. With such a construction, it will be readily apparent that, upon raising and lowering of the rolls 22 and 23, 35 due to the rotation of gear 47, each set of rolls will remain in contact with the sheet the same length of time so that if the rolls are driven at the same speed, the rearward movement of the sheet would be the same as the 40 forward movement. However, the rearwardly operating rolls 23 are adapted to be driven at a relatively slower peripheral speed so that the rearward movement of the sheet may be relatively less than the forward movement. 45 By way of example, the peripheral speed of the forwardly operating rolls could be sixty feet a minute and the peripheral speed of the rearwardly operating rolls fifty feet per minute so that, upon each reciprocation of the 50 sheet within the leer, it would be advanced through the leer ten feet providing, of course, the reciprocation took place once per minute.

The means disclosed in Fig. 1 for operating the pitman 44 is different from that illustrated in Fig. 3. Thus, the pitman 44 is slidably mounted through a sleeve 50 and carries at its outer end a roller 51 operating within a cam groove 52 formed in the gear wheel 53. The gear wheel 53 meshes with a worm 54 carried by a drive shaft 55. With this 60 construction, it will be evident that, upon rotation of the gear wheel 53 and due to the particular shape of the cam groove 52, the forwardly operating rolls 22 are adapted to be maintained in elevated position and therefore

in contact with the sheet for a longer period of time than the rearwardly operating rolls 23. With this arrangement, the rolls 22 and 23 can operate at the same peripheral speed but, because the forwardly operating rolls 70 contact with the sheet for a longer period of time than the rearwardly operating rolls, there is a general advance of the sheet through the leer as a whole. 75

In the operation of the invention, the sheet of glass 10, being received upon the runway rolls 17 from the forming machine, is carried forwardly at its speed of formation and delivered at such speed into the leer 21 and, as the sheet is passed into the leer, the rolls 22 are maintained in elevated position to receive the said sheet thereupon. After the sheet is entirely within the leer, the sets of rolls 22 and 23 are alternately raised and lowered by the means disclosed in either Fig. 3 or Fig. 4 so that the sheet is reciprocated back and forth within the leer by these rolls in a manner to advance the sheet through the leer in a step by step fashion. The forwardly operating rolls 22 always rotate in the same direction and at the same speed and likewise the rearwardly operating rolls always rotate in the same direction and at the same speed. Consequently, no reversing means for the rolls and also no speed changing mechanism 85 to vary the speed of rotation of the rolls is necessary so that the construction, operation and maintenance of the leer is greatly simplified. 90

It is to be understood that the form of the invention herewith shown and described is to be taken as the preferred embodiment of the same, and that various changes in the shape, size and arrangement of parts may be resorted to without departing from the spirit of the invention or the scope of the subjoined claims. 100

I claim:

1. A sheet glass annealing leer of the roller type including two sets of rolls for conveying the sheet to be annealed, the rolls of one set alternating with the rolls of the second set, means for driving the rolls of the first set continuously in a direction to convey the glass from the entrance end of the leer toward the exit end thereof, means for driving the rolls of the second set continuously in a direction to convey the glass from the exit end toward the entrance end of the leer, and means for changing the horizontal relation of the two sets of rolls to move them alternately into and out of supporting contact with the sheet such that the peripheral contact of the first mentioned set of rolls with the glass sheet exceeds that of the second mentioned set. 110
2. A sheet glass annealing leer of the roller type including two sets of rolls for conveying the sheet to be annealed, the rolls of one set being alternately arranged with respect to the rolls of the other set, means for driving 120
3. A sheet glass annealing leer of the roller type including two sets of rolls for conveying the sheet to be annealed, the rolls of one set being alternately arranged with respect to the rolls of the other set, means for driving 130

- the rolls of one set continuously in a direction to advance the sheet forwardly through the leer, means for driving the rolls of the other set continuously in a direction to move the sheet rearwardly in the leer, and means for moving the sets of rolls vertically relative to one another alternately into supporting engagement with the sheet.
3. A glass annealing leer of the roller type including two sets of rolls for conveying the sheet to be annealed, the rolls of one set being alternately arranged with respect to the rolls of the other set, means for driving the rolls of one set continuously in a direction to advance the sheet forwardly through the leer, the diameter of the rolls of one set being relatively greater than the diameter of the rolls of the other set, and means for moving the sets of rolls vertically relative to one another alternately into supporting engagement with the sheet.
4. A glass annealing leer of the roller type including two sets of rolls for conveying the sheet to be annealed, the rolls of one set being alternately arranged with respect to the rolls of the other set, means for driving the rolls of one set continuously in a direction to advance the sheet forwardly through the leer, means for driving the rolls of the other set continuously at a relatively slower peripheral speed and in the opposite direction to move the sheet rearwardly within the leer, and means for moving the sets of rolls vertically relative to one another alternately into supporting engagement with the sheet, said last mentioned means being constructed so as to maintain the two sets of rolls in engagement with the sheet for an equal length of time.
5. A glass annealing leer of the roller type including two sets of rolls for conveying the sheet to be annealed, the rolls of one set being alternately arranged with respect to the rolls of the other set, means for driving the rolls of one set in a direction to advance the sheet forwardly through the leer, means for driving the rolls of the other set in a direction to move the sheet rearwardly within the leer, said sets of rolls being driven at the same rate of speed, with the diameter of the forwardly operating rolls being relatively greater than the diameter of the rearwardly operating rolls, and means for moving the sets of rolls vertically relative to one another alternately into supporting engagement with the sheet, said last mentioned means being of such character as to maintain the two sets of rolls in engagement with the sheet for an equal length of time.
6. A glass annealing leer of the roller type including two sets of rolls for conveying the sheet to be annealed, the rolls of one set being alternately arranged with respect to the rolls of the other set, means for driving the rolls of one set in a direction to advance the sheet forwardly through the leer, means for driving the rolls of the other set in a direction to move the sheet rearwardly within the leer, the diameter of the rolls of one set being relatively greater than the diameter of the rolls of the other set, and means for moving the sets of rolls vertically relative to one another alternately into supporting engagement with the sheet.

Signed at Toledo, in the county of Lucas and State of Ohio, this 26th day of November, 1930.

JOHN L. DRAKE.
